CLAIM

The ornamental design for a warming unit for eyelash press,
as shown and described.

DESCRIPTION

FIG. 1 is a front perspective view of a warming unit for
eyelash press showing my new design, shown in an environment
of use;

FIG. 2 is a front view of thereof, shown with the environment
removed;

FIG. 3 is a rear view of the warming unit for eyelash press
of FIG. 2.

FIG. 4 is a left view of the warming unit for eyelash press
of FIG. 2.

FIG. 5 is a right view of the warming unit for eyelash press
of FIG. 2.

FIG. 6 is a top view of the warming unit for eyelash press
of FIG. 2.

FIG. 7 is a bottom view of the warming unit for eyelash
press of FIG. 2; and,

FIG. 8 is a rear perspective view of the warming unit for
eyelash press of FIG. 2.

The broken lines illustrate portions of the article and form no
part of the claimed design. The broken line disclosure of the
eyelash press illustrates the environment and forms no part
of the claimed design.
